(57) **CLAIM**

The ornamental design for a mini elliptical machine as shown and described.

DESCRIPTION

1. Mini elliptical machine

1.1 is a perspective view of a mini elliptical machine embodying the design;

1.2 is a right side elevational view thereof;

1.3 is a left side elevational view thereof;

1.4 is a front elevational view thereof;

1.5 is a rear elevational view thereof;

1.6 is a top plan view thereof; and

1.7 is a bottom plan view thereof.

The broken line showing of portions of the mini elliptical machine is for the purpose of illustrating portions of the article which form no part of the claimed design.
